UNITED STATES PATENT OFFICE.

EDWIN W. LODGE, OF NORFOLK, VIRGINIA, ASSIGNOR OF ONE-FOURTH TO FREDERICK D. COCK, OF HAMPTON, VIRGINIA.

HEADLIGHT SCREEN.

Application filed January 31, 1922. Serial No. 533,075.

To all whom it may concern:

Be it known that I, EDWIN W. LODGE, a citizen of the United States, residing at Norfolk, in the county of Norfolk and State of Virginia, have invented certain new and useful Improvements in Headlight Screens, of which the following is a specification.

My invention relates to head light screens.

The object of the invention is to provide

10 a simple attachment for automobile head lamps so arranged as to avoid blinding of automobile drivers when approaching each other, at the same time providing sufficient illumination for the roadway.

15 A further object of the invention is to provide a screen or shield stamped from a single piece of metal for fixed beams of light also provided with adjustable means whereby the beams may be directed downward at any angle as desired.

20 Further objects and advantages will be more fully described herein and specifically pointed out in the claim hereunto annexed, recourse being had to the accompanying 25 drawings forming a part of this specification in which:

Figure 1 is a front view of my screen or shield showing both the fixed and movable slats or light projecting strips.

30 Figure 2 is a front view of the inner ring which is provided with movable slats.

Figure 3 is a side elevation of Figure 1.

Figure 4 is a fragmentary plan of the inner ring showing bent up portions of the inner side periphery thereof.

Figure 5 is a similar view of the ring with slits therein before being bent upwards as in Figure 4.

Figure 6 is a side view of one of the 40 movable slats.

Figure 7 is a fragmentary plan of the same at one end.

Figure 8 is a perspective view of one end of the movable slats.

45 Figure 8A is a perspective view of a portion of the inner ring showing the turned up portions or bearings.

Figure 9 is a cross sectional elevation of the upper portion of my complete device.

50 Figure 10 is a perspective fragmentary view of a portion of the outer screen member

and one end of a single light deflecting fixed slat.

Figure 11 is a fragmentary view of the upper part of the screen showing a modification for operating the movable slats. 55

Figure 12 is a front view of the same.

In the drawings like reference numerals indicate similar parts in all the several views: 60

Referring to Figure 9, 1 is the ordinary head lamp body and 2 is the beaded flange by which the glass 3 is held in place and over which my improved screen is placed.

55 My invention consists of the stamped metal ring or dished member 4 and is offset from the flange 5 in such a manner as to leave a space between the inner front surface and the flange for the reception of the hereinafter described inner ring. 65

The outer surface of the screen ring 4 is provided with slats or light deflectors 6 formed at the same time as the ring 4 itself, when stamped from a single piece of metal, and are joined or formed to the ring by the 70 curved ends 7, Figure 10.

75 As shown, the slats or deflectors have a fixed angle for throwing the light beams at a certain declination and are disposed at a certain distance apart thus making the 80 spaces 8 between them, as in Figure 1.

9 is a flat metal ring and is placed within the screen ring 4 usually midway between the outer flat portion or "bulge" of the ring and the glass or lens 3, as shown in Figure 9. 85

The inner periphery of the ring is provided with tangential slits 10 and diametrical slits 11, Figure 5, which form tongues or lugs when bent upwards so as to form bearings 12 for the movable slat pins 14, as 90 shown in Figures 8A and 9.

In Figure 2, the lugs 13 have the same functions as those at 12 and the former may be soldered to the ring and both arranged in staggered alignment as shown in Figure 95 2.

15 are the movable slats or light deflectors and are located between the fixed slats 6 and consequently disposed in the spaces 8, as shown in Figure 1.

100 At each end of the slats a slit is made and a corner turned down forming a notch 16,

Figure 7, and the tongue formed is bent over and holds the pin 14, Figure 6, as at 17, which produces the depending end 18 and consequently the set back corner 19, as 5 shown.

The object of the parts 18 and 19 are for engaging the inner edge of the inner ring 9 and thereby prevent rattling in any position of the movable slats.

10. The slats are provided with a transverse slot, Figures 1 and 12 through which passes the rod 21 by which they are operated.

22 are washers or projections on the rod 21 and are placed above and below each of 15 the movable slats 15 so that when the rod is raised or lowered they may be made to assume different angles, as shown.

20 The slots 20 permit the rod to pass inwards so as to keep the washers 22 in striking alignment with the slats regardless of their angle, as indicated in Figure 9.

25 The rod 21 has a bracket 23 for the guidance of its lower end, Figure 3, also an offset 24 at its upper end for attachment to the cam disc 25 pivoted at 26 on the ring 4 and has a handle 27 by which the cam is operated and consequently the raising and lowering of the slats is effected.

30 In Figures 11 and 12 I show a modified form for locking the slat operating rod 21. In this view I provide a bend 28 at right angles to the rod at its upper portion which is locked in the plate 30 supported by the bracket 29.

35 The plate is provided with horizontal slots 31 and vertical slots 32 forming an L shaped opening similar to a bayonet joint

so that the rod may be locked at its highest or lowest position corresponding to a horizontal or angular position of the slots, respectively. 40

The slats 15 are capable of assuming any angle when the rod 21 is operated and working in conjunction with the fixed slats 6, makes it possible to increase or decrease the 45 amount of light from the lamp. The main ring 4 is stamped out from a single piece of metal by means of suitable dies and is therefore cheap to produce.

The movable slats are joined to the ring 50 9 in such a manner as will not readily get out of order and the whole provides an efficient screen which may be sold at a reasonable price.

55 I claim:

A head light screen, and in combination with a ring, of fixed downwardly projecting slats formed therewith, an inner ring in the rear of the first named ring having slit portions in its periphery for bending into 60 lugs or ears, of movable slats across the diameter of the inner ring having pins upon the ends thereof, and bearing means for the pins on the slats formed by opening said slits, and cam locking and unlocking means 65 for operating said movable slats.

In testimony whereof I have hereunto affixed my signature in the presence of two witnesses.

EDWIN W. LODGE.

Witnesses:
